Attorney

UNITED STATES PATENT OFFICE.

ROBERT MUIR, OF O'FALLON, ILLINOIS.

ADJUSTABLE WINDOW SHADE AND CURTAIN SUPPORT.

1,111,669.

Specification of Letters Patent. Patented Sept. 22, 1914.

Application filed May 21, 1913. Serial No. 769,061.

To all whom it may concern:

Be it known that I, ROBERT MUIR, a citizen of the United States, residing at O'Fallon, in the county of St. Clair and State of Illinois, have invented new and useful Improvements in Adjustable Window Shade and Curtain Supports, of which the following is a specification.

This invention relates to adjustable window shade and curtain supports, the object of the invention being to provide a support of this character which is adjustable to hold a shade roller at any desired elevation upon the window frame, and which is also adjustable to receive and accommodate shade supporting rollers of different lengths for different widths of windows.

A further object of the invention is to provide a support of the character described which is simple of construction, inexpensive of production, ornamental in character, adapted to be readily and conveniently manipulated, and which is designed to hold the shade roller so that the shade can be adjusted without interference from the other parts of the appliance.

The invention consists of the features of construction, combination and arrangement of parts hereinafter fully described and claimed, reference being had to the accompanying drawing, in which,

Figure 1 is an inner elevational view of a window frame showing the application of the invention thereto. Fig. 2 is an end elevation of the same. Fig. 3 is a vertical transverse section through the shade supporting brackets and their telescopic connection. Fig. 4 is a detail perspective view of a portion of one of the brackets and a co-operating cap or end piece. Fig. 5 is a view of one of the curtain pole supports and cord guides. Figs. 6 and 7 are detail views of the cord retaining plate.

Referring to the drawing, 1 designates a window frame upon which are mounted suspension devices shown in the form of screw hooks 2, in proximity to which are arranged hooked supporting devices 3 for a curtain pole 4, each of which supporting devices 50 comprises a length of wire bent to form a pole receiving hook 5, a threaded shank 6 to enter the window frame and an intermediate guiding depression 7.

8 and 9 designate curtain roll supporting brackets of elbow form, the upper arm of each bracket being provided with a guide

opening 10 and the lower end of the lower arm of each bracket being provided with a partially circular enlargement 11 having diametrically disposed notches 12. The enlargements 11 of the respective brackets have openings 13 receiving the outer ends of a pair of tubes 14 and 15 forming a telescopic connection between the brackets, by which the brackets are rendered relatively 65 adjustable toward and from each other to accord with any ordinary width of window frame and to receive shade supporting rollers of different lengths.

The brackets and their telescopic connection provide a vertically adjustable frame to support the shade roller 16, said brackets being respectively provided at the junctures of their arms with oblong and circular openings to receive the angular end of the spring shaft of the roll at one end of the roll and the journal at the opposite end of the roll. As shown, the projecting ends of the tubes 14 and 15 are provided with caps or end pieces 17 and 18, giving an ornamental 75 finish, said caps being formed with tongues 19 bent into engagement with the notches 12 to hold the parts in engagement, and each cap also having a guide slot or opening 20.

A looped suspending cord 21 extends 85 through the telescopic tubes 14 and 15 and through the said slots or openings 20 in the caps and thence upward on the outside of and through the openings 10 in the upper ends of the brackets, the ends of the cord 90 thence passing through the hooks 2 and depressions 7 of the supporting devices 3 and being knotted or united, as at 22, at one side of the window frame, from which point a portion of the cord depends in the form 95 of an operating portion 23. It will thus be understood that the bracket carrying frame is suspended by the cord from the supports 2 and 3 over which the cord is free to run, and that the cord is also free to slide 100 through the telescopic connection and guide openings 10, thus allowing the frame to be conveniently adjusted upon the window frame to any elevation desired.

For the purpose of holding the free end 105 or operating portion 23 of the cord, I provide a spring retaining plate 24 intermediate secured in a vertical position on the frame by a screw or other suitable fastening 25, the lower end of said plate forming a 110 spring arm having its extremity 26 outwardly bent or deflected so that the cord

may be inserted beneath the same and clamped against the window frame. The upper arm of the plate is provided with a punched out spur or projection 27 adapted 5 to enter the frame to hold the plate from pivotal movement, as will be readily understood.

It will be seen from the foregoing description that my invention provides a window shade and curtain support which 10 may be applied to any ordinary window frame and which is adjustable to any elevation on the frame and to receive shade rollers of different lengths as occasion requires. By the use of elbow shaped brackets it will be observed that the shade roller 15 will be mounted in such manner that it will project out partially beyond the plane of the telescopic tubes, so that the shade may 20 be adjusted without interference.

I claim:—

1. The combination with a window frame, of suspending members on said frame, pole supporting members on the 25 frame provided with cord guides, a shade supporting frame, a looped suspending cord extending continuously through the shade supporting frame and over said suspending members and through said guides, and 30 means upon the frame and engageable with the terminals of the cord to hold the shade supporting frame at a desired elevation.

2. The combination with a window frame, of suspending members on said frame, shade 35 supporting brackets provided with guide openings at their upper ends, a tubular telescopic connection between the lower ends of the brackets, and a looped suspending cord extending continuously through said

guide openings and telescopic connection 40 and over said suspending members.

3. The combination with a window frame, of suspending members on said frame, elbow-shaped supporting brackets provided with guide openings at their upper ends, a 45 tubular telescopic connection between the lower ends of the brackets, and a suspending cord extending through said guide openings and telescopic connection and over said suspending members. 50

4. A fixture of the character described comprising suspending members, elbow-shaped supporting brackets provided with guide openings at their upper ends, telescopic tubes fitted in openings in the lower 55 ends of the brackets, slotted caps engaging the brackets and covering the ends of the tubes, and a suspending cord extending through said guide openings, telescopic tubes and caps and over said suspending 60 members.

5. A fixture of the character described comprising suspending members, a shade supporting frame, a looped cord rove through said frame and over said suspending members, and a clamp for holding the free end of the cord, said clamp comprising a spring plate centrally secured and having a deflected lower end and provided with a window frame engaging spur at its upper 70 end to hold it from pivotal movement. 65

In testimony whereof I affix my signature in presence of two witnesses.

ROBERT MUIR.
